MUSICAL INSTRUMENT

Daniel P. O'Brien, Stamford, Conn.

Application April 26, 1941, Serial No. 390,441

2 Claims. (CL 84—1.15)

The invention here disclosed relates to musical instruments of the piano type, having tuned strings, reeds, bars or the like which are vibrated to create the desired musical sounds.

Objects of the invention are to obtain with such instruments, further or additional desirable or amplified sound effects and particularly to accomplish this without impairing or objectionably affecting the sonorous or distinguishing individualistic characteristics of the original instrument.

Thus it is a further object of the invention to provide sound amplifying means for building up the tone and volume characteristics of a piano and which will be directly applicable to such an instrument without modifying, changing or eliminating any functional parts of the piano and which will retain and utilize to the full extent, the sonorous quality of the soundboard and the other desirable characteristic elements of such an instrument.

Other and further objects of the invention are to provide structural means for accomplishment of the foregoing which will be of simple, inexpensive form, taking up small space and readily applicable to existing musical instruments.

Other desirable objects and accomplishments of the invention will appear as the specification proceeds.

The novel features of structure and combinations of parts by which the purposes of the invention are attained are set forth in the specification following, broadly covered in the claims and illustrated by way of example in the accompanying drawing.

Fig. 1 is a broken partly diagrammatic plan view illustrating an application of the invention to a grand piano.

Fig. 2 is an enlarged broken view as on substantially the plane of line 2—2 of Fig. 1, showing the pickup for the lower register or bass section, the strings appearing in section and indicating diagrammatically an amplifier and sound reproducer connected with the pickup coil.

Fig. 3 is a broken bottom plan view of parts shown in Fig. 2.

Fig. 4 is a diagrammatic representation and part sectional view as on line 4—4 of Fig. 2.

In the present disclosure, a practical embodiment of the invention is shown applied to and combined with a grand piano having the usual plate or frame 5, carrying the strings 6, 7 and 8 of the lower, middle and upper registers, the soundboard 9 and other usual parts of such an instrument being present and undisturbed by application of the invention to the instrument.

In the present illustration, a separate single pickup is provided for each of the three string sections of the piano and each one of these pickups, as particularly shown in the detail views, 5 Figs. 2, 3 and 4, comprises a permanent magnet 10 supported across the strings by a bridge piece 11 and carrying a flat pickup coil 12 extending about all the strings of that group.

The supporting elements 11 may be simply 10 pieces of wood of the proper length, rested or secured on the rib portions of the frame in proper position to hold the magnets 10 over the strings and the flat coil 12 freely surrounding the particular group of strings.

15 The magnets 10, of which there are three in the illustration, are shown as permanent bar magnets polarized transversely, across a lesser dimension and arranged with the poles vertically disposed, to project magnetic fields such as indicated at 13 in Fig. 4, intercepting the wires of the coils and inducing currents therein.

The tuned strings, set into vibration in this instance by the hammers of the piano, extending freely through the coils, vary the E. M. F. induced in the coils, in accordance with amplitude, 25 direction and continuity of vibration.

Accordingly, amplifying and reproducing apparatus such as that represented by the amplifier 14 and speaker 15 in Fig. 2, connected with the 30 coil as by wiring 16, will build up and create tonal effects related to those originated by the vibrating strings.

Sustained sound effects are obtainable so long as the strings continue in vibration and this, in 35 the illustration, may be controlled by holding down the keys for so long as such effects are desired. On the other hand, instantaneous cutoff is obtained when a key is released because of the damper operation of the piano action.

40 The resonating, sonorous and other desirable characteristics of the soundboard also are utilized in the present invention since it is undisturbed and left free to fully cooperate with the strings. In fact, the soundboard may desirably be utilized

45 as the resonator element of the speaker and which may be accomplished by mounting the speaker unit so as to apply its vibrating impulses direct to this board.

The pickup coil, surrounding all the strings 50 of a group, such as the bass, voice or treble group, is operative to pick up vibrations of adjoining strings in a group set in motion by sympathetic reaction.

55 The invention is effective with strings of non-magnetic as well as with the usual steel piano

wire strings, because of the eddy currents created in the non-magnetic wires.

By providing separate pickups for the bass, middle and upper registers, the matter of installation in the piano is simplified. One or more or all such pickups may be installed or used and in playing, any one of such controls may be amplified to greater or lesser extent in respect to the others, thus to bring out different desired musical effects.

Various means may be employed for securing the parts. In the illustration, bands 17 are shown passed about the magnets 10 and the supports or struts 11, these bands secured at the top by screws 18, and in similar fashion, the coils are shown secured to the bottom of the magnets 10 by bands 19 secured at the top by screws 20.

The provision of a separate pickup for each string group enables use of speakers best suited to the respective groups, or using to advantage, a speaker of the coaxial type having separate so-called "tweeter" and "woofer" sections and which, for example, may be connected respectively with the treble and bass pickup coils.

Various electrical connections may be employed. The different pickup coils may be connected, through amplifiers, with different speakers or with individualized sections of the same speaker and they may be connected in parallel or in series order with the same or different speakers, as found to give the best desired results under various circumstances.

While one magnet to each coil, extending longitudinally of the coil and polarized transversely

across the coil, is practical and desirable, it is contemplated that a second, oppositely poled magnet may be placed at the opposite side of the pickup coil. While electromagnets may be used, permanent bar magnets are preferred, because of their occupying less space for the magnetic force provided and the freedom from external energizing circuits, etc. These permanent magnets may be of nickel-aluminum alloy, the same having been found to provide the desired high degree of magnetic force within the necessary space limits and for an indefinite period of time.

What is claimed is:

- 15 1. A musical instrument, comprising tuned vibrating sound emitting elements, an elongated pickup coil looped about said tuned vibrating sound elements, an elongated permanent magnet extending along one side (only) of said elongated coil and polarized along a transverse dimension of the same and sound reproducing means connected with said pickup coil.
- 20 2. A musical instrument, comprising tuned metallic strings, an elongated pickup coil looped transversely about said strings, an elongated permanent magnet at the outside of said coil and extending along one side only of said elongated coil, said magnet being polarized along a transverse dimension and creating a magnetic field extending in the direction of extent of said tuned metallic strings and sound reproducing means connected with said elongated pickup coil.

DANIEL P. O'BRIEN.
